Primary Examiner — George D. Kirschbaum*Assistant Examiner* — Joseph J Kukella(74) *Attorney, Agent, or Firm* — Raymond Y. Chan; David and Raymond Patent Firm(57) **CLAIM**

The ornamental design for a lamp for warning, as shown and described.

DESCRIPTION

FIG. 1 is a perspective view of a caution light showing our new design.

FIG. 2 is another perspective view thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

In the drawings, the broken lines depict portions of the lamp for warning that form no part of the claimed design.
